DESIGN FOR AN AIRPLANE

Earl Schuyler Kleinhans, Santa Monica, Calif.,
assignor to Douglas Aircraft Company, Inc.,
Santa Monica, Calif., a corporation of Delaware

Application November 30, 1936, Serial No. 66,211

Term of patent 7 years

To all whom it may concern.

Be it known that I, Earl Schuyler Kleinhans, a citizen of the United States, residing at Santa Monica, in the county of Los Angeles and State of California, have invented a new, original, and ornamental Design for an Airplane, of which the following is a specification, reference being had to the accompanying drawings, forming part hereof.

Fig. 1 is a plan view;

Fig. 2 is a front elevational view of my new design and shows the auxiliary floats (1) retracted into recesses in the underneath side of the wing; and

Fig. 3 is a side elevational view showing my new design.

I claim:

The ornamental design for an airplane as shown.

EARL SCHUYLER KLEINHANS.
